UNITED STATES PATENT OFFICE.

CARL EICKEMEYER, OF BROOKLYN, NEW YORK.

RAIL JOINT.

Application filed June 8, 1926. Serial No. 114,392.

The present invention relates to improvements in rail joints embodied in my specification, Serial No. 688,364, filed January 25th, 1924.

- 5 The improvements embodied in the present specification make the operation of the rail joint covered by prior specification absolutely safe and efficient under all conditions of operation.
- 10 In the prior invention, the splice bar bolts, the splice bars and the wedge formed by the angular under slope of the rail head, prevent any outward pressure of the angular cut surfaces of the joint, should these said 15 angular cut surfaces come together, from expansion or rail creeping, thereby forcing the inner surface of the rail head out of alignment.

Expansion and contraction of the rail are 20 due to changes of temperature; rail creeping is due in part to brakes applied in stopping trains, the weight of which skids along the track, carrying the rail with it.

Rail creeping can be eliminated by spiking 25 the rail base flange to the ties, with spikes in tightly fitting slots in the said rail base flange, allowing every tie to exert its proportional share in checking the rail creeping force.

- 30 The present invention relates to a simpler method of counteracting the said rail creeping, and at the same time take the spreading force off the splice bar bolts, resulting in railroads of exceptionally great mileage, 35 wherein the track bolts or the splice bar bolts are not kept tightly secured, as is the case in railroads of short extent, on account of the greater cost of maintenance of way occasioned in the former.

- 40 To accomplish the desired safe conditions of operation herein enumerated, I spike the splice bar base flanges to the corresponding ties under the joint to give the said splice bars a fixed position.

- 45 A bracket on each side of the rail web, the three (plates) united together, takes the outline of the rail sides, i. e., the angular slope of the under part of the rail head, the outline of the web side, and the rail base flange.

- 50 The said bracket also in greater part takes the outline of the end of the splice bar, against which it abuts, in case of rail expansion or rail creeping.

Inasmuch as the under head slope, the

rail web contour and the flange of the rail 55 are not symmetrical, I make the said bracket interchangeable, so that one drop forging will do for four brackets per joint.

In describing the invention in detail, reference is had to the accompanying drawings 60 which, form a part of this specification, wherein like characters of reference indicate corresponding parts throughout the several views, and wherein:

Fig. 1 represents a plan view of my improved rail joint, showing the ends of two railroad rails, A and A¹, angularly cut in surfaces a and a¹, and carrying as fixed parts of the rail ends, brackets a² and a³ fastened by rivets a⁴ and a⁵ to the rail webs 70 a⁶ and a⁷, rail end splice bars B and B¹, being secured or clamped on either side of the rail ends A and A¹, by means of bolts b and b¹ which pass through openings a⁸ and a⁹ in rail webs a⁶ and a⁷ and b² and b³ in splice bars B and B¹, splice bar bolts carrying nuts b⁴ and b⁵ and lock washers b⁶ and b⁷. Splice bars B and B¹ have openings b⁸ and b⁹ for spikes or other means of fastening to ties C, 75 C¹ and C² in a fixed position.

Fig. 2 represents a side elevation of my improved rail joint, showing rail ends A and A¹, angularly cut surfaces a and a¹, brackets a² and a³, fastened by rivets a⁴ and a⁵, splice bar B, bolts b and b¹, nut b⁴ and lock washer b⁶, bolt openings b² and a⁹, spike openings b⁸ and ties C, C¹ and C², to which the said 80 splice bars B and B¹ are spiked in fixed position.

Fig. 3 is a vertical transverse section 90 through line 3—3 in Fig. 1, showing splice bar clamping bolts b and b¹, nut b⁴ and b⁵ and lock washers b⁶ and b⁷ in elevation, rail A in vertical section and splice bars B and B¹ in vertical section, line a³ shows outline 95 of outer edge of bracket a², web openings a⁸ and splice bar spike openings b⁸.

Fig. 4 is a vertical transverse section 100 through line 4—4, in Fig. 1, showing rail A in vertical section, to which is united with rivets, bracket a², shown sectioned through plane 4—4.

The operation of my improved joint is as follows:

The rail creeping is checked by the rail 105 flange brackets abutting against the ends of the splice bars. The said splice bars are in a fixed position, the rail is free to expand

axially to the rear and the car wheel is supported by approximately the entire rail or rail head, in passing from one rail to the rail forward, giving a joint without shock or vibration for all conditions of operation.

Having thus described my invention what I claim as new is:

1. In combination with a rail joint, a bracket attached to the rail web to abut against the ends of the rail joint splice bar, for the purpose described.
2. In combination with a rail joint, a bracket attached to the rail web, the said bracket forming a surface to abut against the ends of the rail joint splice bar, the said bracket being interchangeable for the purpose described.
3. In combination with a rail joint, splice bars spiked or fastened in fixed position on ties, a rail bracket with surface for abutting

against the end surface of the said splice bars, for the purpose described.

4. In combination, a pair of abutting rail ends, splice bars for joining the rail ends, an anti-creeping means located upon each of the rails at opposite ends of the splice bars and positioned to engage the splice bars, said anti-creeping means comprising each a pair of members having portions lying against the webs of the rails, upper parts engaging beneath the ball of the rail and lower parts engaging the flange of the rail, and end flange portions extending at substantially right angles outwardly from the webs of the rails, and means for securing said anti-creeping means to the rails.

In testimony that I claim the foregoing as my invention, I have signed my name hereto.

CARL EICKEMEYER.
